WELL PUMP

Orville Lee Bishop, Wendell, Idaho

Application June 10, 1941, Serial No. 397,469

1 Claim. (CL 103—6)

The present invention relates to new and useful improvements in well pumps and has for its primary object to provide, in a manner as hereinafter set forth, an apparatus comprising a novel construction, combination and arrangement for elevating and storing water and air under pressure in a single tank.

Other objects of the invention are to provide a power operated pressure pump of the aforementioned character which will be comparatively simple in construction, strong, durable, highly efficient and reliable in operation, compact, and which may be manufactured and installed at low cost.

All of the foregoing, and still further objects and advantages of the invention will become apparent from a study of the following specification, taken in connection with the accompanying drawings, wherein like characters of reference designate corresponding parts throughout the several views, and wherein:

Figure 1 is a view in side elevation of an apparatus constructed in accordance with the present invention, showing the housing in vertical section.

Figure 2 is a view principally in vertical section through the lower portion of the apparatus.

Figure 3 is a detail view in vertical section, taken substantially on the line 3—3 of Figure 2.

Figure 4 is a view in vertical section through the lower portion of the air pump.

Figure 5 is a view in horizontal section, taken substantially on the line 5—5 of Figure 1.

Referring now to the drawings in detail, reference character 1 designates a housing or enclosure. The housing 1 may be of any suitable material and dimensions. In the embodiment of the invention what has been illustrated, the housing 1 is positioned at the top of the well 2.

Mounted on the housing 1 is a suitable pump operating mechanism 3. Extending from the pump operating mechanism 3 through the housing 1 into the well 2 is a casing 4. Mounted in the housing 1 is a storage tank 5. A suitable power plant 6 is mounted on the housing 1 and drives the pump operating mechanism 3 through a belt and pulley connection 7. A pressure operated switch 8 on the storage tank 5 controls the power plant 6.

Mounted in the casing 4 is a rod 9 which is actuated by the pump operating mechanism 3. Swivelly connected at 10 to the lower end of the pump rod 9 is a plunger rod 11. A pair of cup washers 12 are adjustably mounted on the threaded lower end portion of the plunger rod

11, said cup washers being operable in a cylindrical lining 13 in the lower portion of the casing 4. Mounted between the cup washers 12 is a rubber expander 14. An adjusting nut 15 is provided above the upper cup washer 12.

Threaded on the lower end portion of the casing 4 is a cast head 16 which is formed to provide chambers 17 and 18, said chambers communicating with each other through a passage 19. A tube 20 is threaded into the lower portion of the chamber 17 of the head 16. Operable in the tube 20 is a sucker rod 21 which is connected by a coupling 22 to the plunger rod 11. The tube 20 extends downwardly into the well and is provided, on its lower end, with a suitable pump or working barrel which is actuated by the sucker rod 21.

Mounted on the head 16 is an air pump 23. The pump 23 includes a cylinder 24 which is threaded secured to the head 16 and which communicates with the chamber 18 through an angular passage 25 in said head. Mounted in the lower end portion of the cylinders 24 is a rubber seat 26 with which a spring seated ball check valve 27 is engageable.

Operable in the cylinder 24 is a plunger comprising cup washers 28 which are adjustably mounted on the lower end portion of a rod 29. Adjacent its lower end, the casing 4 has formed therein a vertical slot 30. Mounted on the rod 11 and projecting horizontally therefrom are arms 31 which are operable in the slot 30 and which terminate at their outer ends in eyes 32. The rod 29 extends upwardly above the cylinder 24 and passes through the eyes 32 in which it is secured by nuts 33. It will thus be seen that the air pump 23 is connected to the rod 11 for actuation thereby. A block 34 is mounted between the arms 31 and travels in the slot 30.

Threaded into the lower end portion of the chamber 18 of the head 16 is a suitable relief valve 35. Threaded into the upper end portion of the chamber 18 and rising from the head 16 is a discharge pipe 36. The upper end of the pipe 36 is connected to the storage tank 5. Interposed in the upper portion of the pipe 36 is a check valve 37.

It is thought that the operation of the apparatus will be readily apparent from a consideration of the foregoing. On the upstroke of the sucker rod 21, the plunger comprising the elements 11 and 12 moves upwardly, at the same time raising the plunger of the air pump 23. The cup washers 12 prevent the water from passing upwardly in the casing 4. Of course, the

fluid may rise to the level of the lowermost washer 12. The fluid flows through the passage 19 into the chamber 18. On the downstroke of the sucker rod 21 the fluid above the level of the passage 19 is forced therethrough into the chamber 18 and at the same time air under pressure from the pump 23 is forced into said chamber 18. The fluid and air are forced upwardly through the discharge pipe 26 past the check valve 37 into the storage tank 5. A rubber expander 38 is provided on the rod 29 between the cups 28.

It is believed that the many advantages of a well pump constructed in accordance with the present invention will be readily understood, and although a preferred embodiment of the apparatus is as illustrated and described, it is to be understood that changes in the details of construction, and in the combination and arrangement of parts, may be resorted to which will fall within the scope of the invention as claimed.

What is claimed is:

A well pump of the character described comprising a casing, a plunger operable in said casing, a mechanical pump operating unit operatively connected to the plunger for actuating the same; a head at the lower end of the casing, a tube depending from said head; a suction plunger mounted in the bottom end of said tube to draw water therein, a sucker rod operable in the tube and head connecting the plunger and suction plunger together; a liquid discharge pipe connected to the head; arms on the plunger operable in a vertical slot in said casing; an air pump mounted on the head and secured to the arms for actuation by the plunger, the air from the air pump to discharge into the liquid discharge pipe, and a storage tank connected to the discharge pipe for receiving water and air under pressure therefrom.

20

ORVILLE LEE BISHOP.
